UNITED STATES PATENT OFFICE.

DAVID GRAVEL, OF CHATTANOOGA, TENNESSEE, ASSIGNOR TO BARBER-COLMAN COMPANY, OF ROCKFORD, ILLINOIS, A CORPORATION OF ILLINOIS.

KNOT-TYING MECHANISM.

Application filed March 12, 1923. Serial No. 624,403.

The invention relates to knot-tying mechanisms such as are commonly employed in textile mills for the purpose of uniting threads; and it has particular reference to a device of this character which is capable of tying a small flat knot such as is ordinarily termed in the art a "weaver's knot".

Numerous efforts have been made in the past to produce a practical knotter for tying the true weaver's knot, or a variant thereof, but such devices have met with limited commercial success for various reasons, chief among which is the fact that it has been hard to hold the parts of the knot from improper shifting movement during the operation of the knotter, this trouble being perhaps due to the difficulty in maintaining the correct degree of tension on the various strands.

20 It is the object of my invention to produce an implement to the weaver's knotter type which shall be of a thoroughly practical character by reason of the reliability with which it holds and operates upon the threads.

25 An important object of the invention is to produce an implement of this character which is comparatively simple in construction.

In the accompanying drawings, Figure 1 30 is a side elevation of my improved knotter, illustrating the manner in which the device is mounted upon the hand of the operator. Fig. 2 is a fragmentary elevational view taken from the opposite side of the knotter. 35 Fig. 3 is a fragmentary plan view. Figs. 4 and 5 are fragmentary views illustrating details of construction. Figs. 6, 7 and 8 are views similar to Fig. 3 but showing the parts in different relative positions. Fig. 9 is a 40 detail view somewhat diagrammatic in character and illustrating the knot just as it is about to be completed. Fig. 10 is a detail view of the completed knot but before it is drawn taut.

45 It will be observed that I have illustrated only one embodiment of the invention. It is contemplated, however, that various changes in form, construction and arrangement of parts may be made by those skilled in the art without departing from the spirit and scope of the invention as expressed in the appended claims.

I have herein shown a hand knotter of the general type disclosed in Patent No. 75,110

dated March 22, 1904. The present knotter 55 comprises a tying bill to form the loops of the knot and to shear one of the threads; means for tightening the loops of the knot and stripping the knot from the tying bill; means for holding and guiding the threads 60 in proper position for the knot-tying operation; and a shear for severing the other thread. The two threads to be united are herein referred to as a bobbin thread and a spool thread, but these terms are not to be 65 understood as limitations of the invention. The thread marked "bobbin thread" on the drawing might be the spool thread, and the "spool thread" might be the bobbin thread.

It may be here remarked that for the sake 70 of clearness the diameter of the threads has been exaggerated in the views.

Referring now to the drawings, the implement embodies a handle A⁶ and a strap A⁷ together forming a loop whereby the device 75 may be supported upon the hand of the operative. A standard A is rigidly fixed to the handle A⁶ and is provided with bearings for the shaft C³ (Fig. 8) of the tying bill C⁵. Said tying bill is provided with a 80 pivoted shearing and clamping jaw C¹⁴ arranged to be moved to open and close the tying bill by means of a cam barrel C. The tying bill and its shearing and clamping jaw are fully illustrated in said Patent No. 85 755,110. On the shaft C³ is a spiral gear pinion C⁴ (Fig. 8) that meshes with a spiral gear segment B⁷ (Fig. 1). Said segment is rotatively mounted upon a stud B which is fixed to the handle A⁶. Fixed to the hub of 90 the gear segment is a thumb fork B⁵ by means of which the segment may be oscillated to rotate the tying bill in one direction through one and a half revolutions and in the opposite direction to the initial position. 95

The means herein shown for tightening the loops of the knot and stripping the knot from the tying bill comprises a thread-holding arm E pivoted to swing on the axis D. The forward end of said arm is in the form 100 of a hook E² to receive one of the threads to be tied, for example, the thread extending from the bobbin. A coiled spring E³ (Fig. 1) tends to hold the arm E in its initial position, such position being determined by contact of the arm with a stationary stop A⁸ (Fig. 3).

A thread-clamping arm D⁶, provided at

its forward end with two upwardly-extending clamping fingers D' , that lie at opposite sides of the holding arm E , is pivoted at its rear end to one arm of a bell crank D^4 5 that swings on the axis D . The other arm of the bell crank is provided with a roller stud that lies in a cam groove B^8 (Fig. 8) formed in an arcuate flange B^9 which is fixed with relation to the gear segment B^7 . The 10 shape of the cam groove B^8 is such as to cause the bell crank D^4 to swing back and forth in each stroke of the thumb fork B^5 . During the operating (i. e. downward) stroke of the thumb fork, the arm D^6 is 15 advanced so as to cause the fingers D' to clamp the thread lying in the hook E^2 of the arm E . As the arm D^6 advances, a spring latch E^4 (Fig. 6) on the arm E engages a stud D^8 on the bell crank D^4 , so that when 20 the movement of the bell crank is reversed the arm E is caused to move with the bell crank and the arm D^6 (as in Fig. 6), in which movement the said arms swing laterally away from the tying bill to tighten the 25 loops of the knot and strip the knot off the tying bill. As the thumb fork completes its operative stroke, the spring latch E^4 is disengaged from the pin D^8 by means of a trigger pin E^6 carried by the latch and 30 adapted to engage with a stop pin A^9 on the standard A (Fig. 8).

At the side of the tying bill, opposite to the arms E and D^6 , is a stationary thread guide C^{19} for the thread extending from the 35 spool.

All of the parts thus far described are substantially identical with the parts bearing corresponding reference characters in the before-mentioned patent, with the exception 40 of the hook E^2 which is specially constructed and arranged in a manner which will presently appear.

Cooperating with the thread guide C^{19} for supporting the thread extending from the 45 spool, is a guide formed at the forward end of the arm D^6 by means of an upstanding finger 11 (Fig. 2) spaced a short distance inwardly from the fingers D' . It will be observed that in the movement of the arm 50 D^6 , said thread guide is carried forwardly, the finger 11 near the end of such forward movement coacting with an upstanding finger 12 located near the forward end of the arm E and spaced inwardly from the hook 55 E^2 . The fingers D' coacting with the opposite sides of the hook E^2 constitute a clamp for the bobbin thread lying within the hook; but the finger 11 not being doubled, as in the case of the fingers D' , coacts with the 60 finger 12 to position the spool thread, but without clamping it therebetween. Accordingly, the spool thread is permitted to move relative to the guide 11 in the tying operation. The primary function, therefore, of 65 the guide is to hold the spool thread in prop-

er relation to the tying bill for the initial loop-forming operation, and then to move the spool thread forwardly adjacent the guide hook E^2 for the stripping operation but without placing any tension on the 70 thread. The reason for avoiding tension on this thread is that it results in the production of a slip knot.

The means for supporting the bobbin thread may comprise a bracket 13 (Fig. 6) 75 rigid with the standard A and projecting forwardly and then laterally into an inclined position directly in front of the tying bill. The bobbin thread after passing through the hook E^2 is passed or looped behind the tying bill (see Fig. 3), and then is brought forwardly to the bracket 13 where it is placed in a combined guide and shear device designated generally by the numeral 14. This device comprises a stationary plate 80 15 (Figs. 1 and 4) having an upstanding finger or shear blade 16. A movable shear blade 17 is rigid with an arm 18 pivoted at 19 and provided with an inwardly projecting finger 20 at its lower end. Said finger is arranged to be engaged by the bifurcated end 21 of a lever 22 pivoted upon a post 23 carried by the bracket 13. The opposite or inner end of said lever is bent 85 downwardly for engagement with the arm 24 of the segment B^7 and also with a hooked member 25 carried by the thumb fork B^5 . It will thus be seen that the shear blade 17 is arranged to be reciprocated in the rocking movements of the gear segment, the arrangement being such that near the end of the downward movement of the thumb fork B^5 , the shear 14 severs the thread held thereby; and in the return movement of the thumb fork the clamp is opened to receive a new 90 thread.

Assuming now that it is desired to unite two threads, for example, a bobbin thread and a spool thread, they are placed in the knotter substantially in the relation shown 95 in Fig. 3. One manner of accomplishing this result is to lay the ends of the two threads parallel across the palm of the hand with the fingers toward the body and with the bobbin thread nearest the ends of the 100 fingers. The threads are then placed in the guides E^2 and 11, as shown in Fig. 6. Now by inverting the palm, the bobbin thread may readily be passed behind the bill C^8 and the spool thread in front of it. The free 105 ends of the threads are then manipulated so that the end of the bobbin thread is placed in the shear 14 and the end of the spool thread lies in the thread guide C^{19} . Thus, the threads are crossed and recrossed upon 110 opposite sides of the tying bill (Fig. 3) so that the formation of a pair of overlapping loops a and b is initially effected. The thumb fork B^5 is now depressed, thereby 115 rotating the tying bill in a counterclockwise 120 direction, so that the shear 14 strips the 125 loops a and b from the bill. The bill is then 130 rotated in the opposite direction, so that the shear 14 strips the loops a and b from the bill.

direction. By reason of the relative location of the portions of the threads leading to the bobbin and the spool respectively, as shown in Figs. 3 and 6, the tying bill as it 5 rotates through the first quarter of its revolution engages said threads at a point between them just ahead of their initial crossing. In the continued rotation of the bill through a half revolution, the tying bill 10 twists the loop *a* (Figs. 6 and 7); and as the bill approaches and travels through the final quarter of its first complete revolution, it engages with the free end of the spool thread, cuts it off and clamps the same in a 15 well known manner, the end of the spool thread, in such movement of the bill, traveling with it. In the next quarter of a revolution of the tying bill, the arm *D*⁶ is moved outwardly, carrying the arm *E* with it. 20 Consequently the loops *a* and *b* are stripped from the tying bill while the free end of the spool thread held by the bill clamp is drawn first around the crossed strands of the loop *a* and then through it, as clearly shown in 25 Fig. 9. The end of the bobbin thread remains loose in the shear device 14 while the loops are thus being stripped from the tying bill (Fig. 8) and in the final outward movement of the arms *E* and *D*⁶ the free end of 30 the bobbin thread is severed by the shear device. After the threads have thus been stripped from the bill, and the end of the bobbin thread drawn through the loop *a*, the bill continues to rotate through a quarter 35 of a revolution in which the knot is drawn taut (Fig. 5) and the end of the thread held by the bill clamp finally released therefrom.

It will be observed that the thread guide 11 during the stripping operation (Fig. 8) 40 occupies a position adjacent the hook *E*. The construction is such, however, that the guide allows the spool thread to slide freely therein in order not to place any tension thereon. Thus the knot is drawn taut solely 45 by the tension placed by the tying bill upon the free end of the spool thread on the one hand and upon the portion of the bobbin thread leading to the bobbin, on the other hand.

50 In the reverse movement of the thumb fork, the parts are restored to their initial positions as shown in Fig. 3.

I claim as my invention:

1. A weaver's knotter comprising, in combination, a frame, a rotary tying bill mounted in said frame, an arm mounted on said frame and extending alongside the tying bill to a point forwardly of the frame, the forward end of said arm being bent laterally in 55 front of said tying bill, a member pivoted on said bent portion of the arm, a second member fixed to the arm with which the first member is adapted to coact to shear and clamp the thread, means for actuating the 60 65 pivoted member, and other thread support-

ing means adapted to coact with said members to position and tension the threads in the operation thereon by said tying bill.

2. A weaver's knotter comprising, in combination, a frame and means mounted on said frame for tying a weaver's knot including thread holding means and a rotary tying bill adapted to operate upon a pair of threads supported by said holding means, said thread holding means including an arm carried by the frame and extending alongside the tying bill to a point in front of the tying bill, said arm being bent forwardly of the tying bill and having a pair of members thereon, one of which is mounted for pivotal movement relative to the other member, and means for operating the pivoted member. 75 80

3. A mechanism for tying weavers' knots having, in combination with a tying bill, a thread clamping and stripping device 85 mounted to swing laterally substantially in a plane containing the axis of the tying bill so as to be movable bodily toward and from the tying bill, the free end of said device having means for gripping the threads so as to tighten the knot in the movement of the device away from the tying bill, and the end of the tying bill being disposed substantially in said plane during the stripping operation. 90

4. A mechanism for tying weavers' knots having, in combination with a tying bill, a thread clamping and stripping device mounted to swing substantially in a plane containing the axis of the tying bill so as to be movable bodily toward and from the tying bill, the free end of said device having 95 means for gripping one of the threads lightly and the other tightly and also for moving the lightly held thread relative to the other whereby to relieve the same of tension in the 100 movement of the device away from the bill in the knot-tightening operation. 105

5. In a tying mechanism for weavers' knots, the combination of a tying bill having thread cutting and clamping means and adapted to operate upon two strands crossed on opposite sides of the tying bill, means for holding the strands on each side of the tying bill spaced a substantial distance apart, mechanism for operating the tying bill in 115 relation to said strands to produce interengaging loop formations therein to form the knot, and means for tightening the knot and stripping it from the tying bill including the clamping means of the tying bill 120 adapted to hold one of said strands as the knot is being stripped from the bill, and a device operable to move one of said strands into closely spaced relation to the other to relieve tension thereon while placing tension upon the other one of said strands in the stripping of the knot from the tying bill. 125

6. In a tying mechanism for weavers' knots, the combination of a tying bill having thread cutting and clamping means and 130

adapted to operate upon two strands crossed on opposite sides of the tying bill, mechanism for operating the tying bill in relation to said strands to produce interengaging loop formations therein to form the knot, means for holding the strands a substantial distance apart during the knot-forming operation including a device for gripping both strands on one side of the tying bill, said device being subsequently operable after the formation of the knot to move one of said strands toward the other to relieve it of tension, and means for actuating said device to place tension on said other strand to tighten the knot.

7. A weaver's knotter comprising, in combination, a frame, a rotary tying bill mounted in said frame and having thread cutting and clamping means, and means for posi-

tioning two strands relative to the tying bill so that the tying bill is between the strands and the strands are crossed on opposite sides of the tying bill, said positioning means including a clamp and shear device positioned in front of the tying bill, a guide member positioned laterally to one side of the tying bill a substantial distance from said clamp and shear device, and a combined clamping and stripping device mounted laterally of the tying bill on the side opposite said member, said clamping and stripping device having two guides operable to hold the two strands spaced a substantial distance apart during the knot-forming operation.

In testimony whereof, I have hereunto affixed my signature.

DAVID GRAVEL.
